UNITED STATES PATENT OFFICE

108,472

DESIGN FOR A FLASHLIGHT

Orville T. Wood, Clinton, Mass., assignor to Blake
Manufacturing Corporation, Clinton, Mass., a
corporation of Massachusetts

Application September 29, 1936, Serial No. 65,060

Term of patent 7 years

To all whom it may concern:

Be it known that I, Orville T. Wood, a citizen of the United States of America, residing at Clinton, in the county of Worcester and State of Massachusetts, have invented a new, original, and ornamental Design for a Flashlight, of which the following is a specification, reference being had to the accompanying drawing, forming part thereof.

Fig. 1 is a plan view of the flashlight, showing my new design.

Fig. 2 is a side elevational view of the same,

Fig. 3 is an end view, taken from the rear, and

Fig. 4 is a sectional view, taken on the line 4—4 of Fig. 2, and illustrating the profile of the flashlight casing.

The features which characterize the design comprise a flashlight of the configuration shown and having on its body surface relatively wide and shallow longitudinal flutes extending substantially the full length of the body portion, the ends of said flutes rising gradually and merging into cylindrical surfaces at the ends of the body portion as best shown in Figures 1 and 2 of the drawing.

I claim:

The ornamental design for a flashlight as shown and described.

ORVILLE T. WOOD.
